UNITED STATES PATENT OFFICE.

LOUIS D. BARISH, OF NEW YORK, N. Y.

DESIGN FOR A STOCKING.

Application filed May 19, 1928. Serial No. 26,762. Term of patent 7 years.

To all whom it may concern:

Be it known that I, LOUIS D. BARISH, a citizen of the United States, and a resident of the city of New York, in the county of New York (borough of Manhattan) and State of New York, have invented the new, original, and ornamental Design for a Stocking, of which the following is a specification.

Reference is had to the accompanying drawing, forming part thereof, wherein

I claim:—

The ornamental design for a stocking, substantially as shown.

Signed at New York in the county of New York and State of New York this 17th day of May, 1928.

LOUIS D. BARISH.
